UNITED STATES PATENT OFFICE.

LEOPOLDO CASTRO GELPI, OF VIEQUES, PORTO RICO.

GAME APPARATUS.

Application filed July 23, 1924. Serial No. 727,789.

To all whom it may concern:

Be it known that I, LEOPOLDO C. GELPI, a citizen of the United States, residing at Vieques, in the county of Humacao and Territory of Porto Rico, have invented certain new and useful Improvements in Game Apparatus, of which the following is a specification.

This invention relates to improvements in game apparatus and more particularly to that type embodying a game board having divisions represented upon its surface and game pieces which are movable over the surface of the board and from one division to another, and the primary object of the present invention is to provide a game board and game pieces movable thereover in a manner to simulate the movements of brigades of warring nations, in battle, the arrangement being such, and likewise the principles, that many interesting complications will be encountered in the playing of the game by the use of the apparatus thereby necessitating the exercise of the judgment of the players, so that the playing of the game involves more than the mere element of chance.

In the accompanying drawings:

Figure 1 is a plan view of a game board embodying the invention.

Figure 2 is a group view illustrating the game pieces in plan.

Figure 3 is a perspective view of one of the game pieces.

In the drawings, the numeral 1 indicates in general the game board of the apparatus and the same may be of any suitable material and preferably of the oblong rectangular form shown in Figure 1. Printed upon the face of the board in contrasting colors, are two courses or paths over which the game pieces of the opposing armies are to be moved, one of these paths, as illustrated in Figure 1, being printed, for example, in red, and the other in blue. The numerals 2 and 3 indicate sections of a broken annular path, and the numerals 4 and 5 indicate the sections of another broken annular path, both of these paths being printed in blue and being the ones over which the game pieces representing the forces of one army are to be moved. The numerals 6 and 7 indicate sections of a broken annular path corresponding to the an-

nular path 2, and the numerals 8 and 9 indicate the sections of a broken annular path corresponding to the sections 4 and 5 before referred to. The said sections 4 and 5 are located within the bounds of and concentric to the sections 6 and 7, and the sections 8 and 9 are located within the bounds of and concentric to the sections 2 and 3.

As indicated in Figure 1 of the drawings, the paths comprising the sections 2 and 3 and 4 and 5 are printed blue and the sections 6 and 7 and 8 and 9 are printed red, the first group of sections representing the trenches of one army and the second mentioned group representing the trenches of the other army. If desired, the representation 10 of a cannon may be printed within the bounds of the sections 8 and 9 and the sections 4 and 5. Connection is established between one end of the section 2 and the adjacent end of the section 5 by a diagonal connecting section 11, and likewise, connection is established between one end of the section 3 and the adjacent end of the section 4 by a diagonal connecting section 12, the two sections intersecting. Likewise, connection is established between one end of the section 6 and the adjacent end of the section 9 by a diagonal connecting section 13, and similarly, connection is established between one end of the section 8 and the adjacent end of the section 7 by a diagonal connecting section 14, the connecting sections 11, 12, 13 and 14 crossing one another as shown in the said Figure 1. The numeral 15 indicates a plurality of radial lines which divide the path sections 2 and 8 into spaces which represent successive trenches, and similar lines 16 divide the sections 3 and 9 into similar spaces representing trenches. Likewise, lines 17 and 18 divide the sections 4 and 6 and sections 5 and 7 respectively, into a number of spaces representing trenches. Similarly, lines 19 divide the connecting sections 11, 12, 13 and 14 into spaces representing trenches.

The base for one army is indicated in general by the numeral 19 and the said base comprises an arcuate printed area 20 of the same color, namely blue, as the trench sections 2, 3, 4 and 5, and extends from that end of the trench section 2 which is opposite the connecting section 11, on an arc eccentric to the said section 2, to a point midway be-

tween the end of the section 3 and substantially touching the margin of the said section so that a space 21 is left between the said section 3 and the base section 19. The 5 printed area 20 is divided by the radial lines 22 into a number of spaces 23 and these spaces are designated by ordinals 4, 5, 6, 7, 8 and 9; the ordinal 10 being printed within the space 21. The purpose of so designating the spaces 23 and the space 10, will 10 presently be pointed out. From the last mentioned end of the strip-like area 20, there is extended, along a straight line, tangent to the margin of the trench section 3, 15 a printed strip-like area 24 within the bounds of which are printed a series of circular spots 25, the strip-like area 24 being printed in blue and the spots being printed in red.

20 A strip-like arcuate area 26 is printed upon the face of the board and corresponds in dimensions substantially to the area 19, and this constitutes a safety zone and is divided by a plurality of radial lines 27 25 into a number of spaces 28, the zone being indicated, if desired, by the letter S as indicated by the numeral 29. The area 26 extends from that end of the trench section 3 which is opposite the connecting section 12, to a point midway between the ends of the trench section 2. Extending from the other end of the strip-like area 26 is a straight strip-like area 30 which corresponds to the area 24 and is tangential to the trench section 2 and parallel to the said area 24. The area 30, as well as the area 26, is printed blue, and within the area 30 are printed a number of circular spots 31 which are red in color, the area 30 constituting a prison area, as also the said area 24. It will be observed by reference to Figure 1, that the base and safety areas 19 and 26 intersect at a point between the base ends of the trench sections 2 and 3 to define a substantially triangular space 32 in which are printed ordinals arranged as follows:—

1
5 + 6
2

50 In the angle between the diagonal connecting sections 11 and 14, there is a substantially triangular space indicated by the numeral 33 in which there are arranged ordinals as follows:—

1
6 + 6
1

60 At the point of intersection of the connecting sections 11 and 14 there is printed a circular spot 34 and within the spot the letter W as indicated by the numeral 35, this letter constituting an abbreviation of the words "White cross". Similar spots 36 and

37 are printed upon the face of the board and similarly designated, substantially midway between the ends of the trench sections 2 and 8 and 3 and 9 respectively, the spot 36 occupying a portion of each of the sections 2 and 8 and, likewise, the spot 37 occupying a portion of each of the sections 3 and 9. A spot 38 is also printed upon the face of the board and is designated by the letter W, as in the case of the spot 34, and this spot 38 is located midway between the adjacent ends of the sections 2 and 8 and 3 and 9, and inwardly of the intersection of the strip-like space and safety zone 19 and 26.

80 The numeral 39 indicates an arcuate base zone which is printed upon the face of the board 1 and is red in color and divided by a plurality of radial lines 40 into spaces 41 which are designated successively by the ordinals 4, 5, 6, 7, 8, and 9. The said zone 39 extends from that end of the trench section 7 opposite the end which joins the diagonal connecting section 12, to a point substantially midway between the ends of the trench section 6 and is, like the base zone 19, eccentric to the sections 6 and 7 so that a space 42 corresponding to the space 21 is provided, and in this space there is printed the ordinal 10. Extending from the last mentioned end of the zone 39 and printed upon the face of the board is a prison zone 43 which is in alignment with the prison zone 30 and meets the end of the same. A plurality of blue spots 44 are printed within the bounds of the zone 43 and the said zone is otherwise printed red. The numeral 45 indicates a safety zone which is of arcuate form and corresponds to the safety zone 26 and extends from that end of the trench section 6 opposite the end which connects with the diagonal connecting section 13, to a point substantially midway between the ends of the trench section 11 and is divided by a plurality of radial lines 46 into a number of spaces 47 which correspond to the spaces 28 of the safety zone 26, the said zone 45 being designated by the abbreviation S as indicated by the numeral 48. Extending from the last mentioned end of the zone 45, 90 is a prison zone indicated by the numeral 49, which zone is parallel to the zone 43 and in alignment with the zone 24, meeting the end of the said zone.

100 The zone 49 is printed in red and within the zone are printed a number of blue spots indicated by the numeral 50. A red spot 51 is printed on the face of the board at the juncture of the connecting sections 11 and 12 and corresponds in position to the spot 34 heretofore referred to, and the said spot 51 is designated by the abbreviation R of the words "Red cross" as indicated by the numeral 52. In the angle between the diagonal sections 11 and 12, there is printed, in 110

red, a substantially triangular space or field indicated by the numeral 53 and within the bounds of this field are printed ordinals as follows:—

5   1
10   6-6
15   6

Red spots 54 are printed upon the face 10 of the board midway between the ends of the trench sections 4 and 6 and 5 and 7, and these spots occupy a portion of the respective sections. A similar spot 55 is printed in the space between the ends of the said 15 sections 4 and 6 and 5 and 7 from which the base and safety zones 39 and 45 extend, as shown in Figure, and said spots 54 and 55, as in the case of the spots 51, are designated by the abbreviation R.

20 The intersection of the zones 39 and 45 provides a substantially diamond shaped space indicated by the numeral 56 and corresponding to the space 32, and printed within the bounds of this space are ordinals 25 as follows:—

1
2-6
6

30 Inwardly of the space 32 and between the said space and the adjacent end of the trench section 2, that portion of the zone 19 which connects with the said end of the section 2 is designated by the word "Entrance" as indicated by the numeral 57, and 35 the corresponding portion of the zone 26 is designated by the word "Outlet" as indicated by the numeral 58. In a similar manner, the corresponding portions of the zones 39 and 45 are respectively designated 40 by the words "Entrance" and "Outlet" as indicated respectively by the numerals 59 and 60.

45 One of the game pieces which is employed in playing the game is clearly illustrated in Figure 3 of the drawings and is indicated in general by the numeral 61, the game piece being in the form of a representation of a soldier and representing a brigade. The base of the game piece comprises two 50 laterally projecting parts indicated by the numeral 62. Figure 2 of the drawings represents a plan view of the brigades of the two opposing armies, the upper row in said Figure 2 representing the brigades of one 55 army and the lower row the brigades of the other army.

60 In throwing two dice, there are twenty-one possible combinations of numbers, and in determining the moves to be made by the game pieces of the apparatus embodying the invention, I preferably make use of two dice and take advantage of the said twenty-one possible combinations to determine the movements of the said game pieces. 65 The game pieces representing the brigades

of one army are designated, upon their base portions 62, by the ordinals 2-2, 2-3, 3-3, 3-4, 3-5, 3-6, and 4-6, as illustrated in the upper row of game pieces in Figure 2, there being likewise a game piece indicated 70 by the numeral 63 which represents the red cross unit of the particular army and the base portions 62 of which are preferably colored red. The lower row of game pieces in Figure 2, represents the brigades of the 75 other army and these game pieces bear upon their base portions 62 the ordinals 1-3, 1-4, 2-4, 2-5, 4-4, 4-5, and 5-5, there being another game piece indicated by the numeral 64, the base portions of which are 80 preferably blue in color and represents the white cross unit of this particular army. It will be observed that no two combinations of ordinals are alike and it will likewise be observed that the sum of the ordinals upon the game pieces of each army, arranged as illustrated in Figure 2, total 85 respectively, in succession, 4, 5, 6, 7, 8, 9 and 10.

90 In playing the game, two dice are thrown by the player who is to make the first move, and the game pieces representing the brigades of the two armies having been arranged upon the respectively designated spaces of the base zones 19 and 39, the total 95 of the number thrown will determine which of the game pieces is to be moved. For example, if the number thrown is "six" the player casting the dice will select the game piece designated by the ordinals 3-3 or 100 2-4, depending upon the game pieces with which he is supplied. The player will then move this game piece six spaces along the trench section 2, beginning with the space 57 marked "Entrance." In like manner, the 105 succeeding plays will be made alternately by the players and each game piece indicated to be moved, will be advanced a number of spaces corresponding to the total of the ordinals upon the base portions thereof. 110 Should the dice indicate any of the combinations 1-1 or 6-6 or 1-6, then the game piece 64 or 63, representing the white cross or the red cross, is advanced to position occupying the spot 36 or the spot 37, in the 115 case of the white cross piece, or the spot 54 or spot 54' in the case of the red cross game piece. Should a play made by one player bring one of his game pieces directly opposite the trench space occupied by a game piece of the other player, the last mentioned player will remove his game piece and place it on one of the spots in his opponent's prison area. The occupation of one of the 120 white or red cross spots, by a white or red cross game piece evacuates the four trench spaces or sections at each side of the said spot. A throw by any player indicating the 125 numbers 1 and 2 or 5 and 6, on the one hand, or 1 and 5 or 2 and 6 on the other

hand, permits the player to move any of his game pieces a corresponding number of trench spaces, that is to say, one or two spaces, in the first instance, or five or six spaces and, in the latter instance, one or five spaces or two or six spaces.

Having thus described the invention, what I claim is:

1. In game apparatus, a game board having courses depicted thereon and divided to represent lines of trenches, each course comprising a plurality of sections and the corresponding sections of the two courses being concentrically arranged, the board having also depicted thereon base and safety zones exterior to the sections of the respective courses, and game pieces representing brigades movable over the courses, the base zones having divisions for the initial spacing of the opposing game pieces.

2. In game apparatus, a game board having courses depicted thereon and divided to represent lines of trenches, each course comprising a plurality of sections and the corresponding sections of the two courses being concentrically arranged, the board having also depicted thereon base and safety zones exterior to the sections of the respective courses, and game pieces representing brigades movable over the courses, the base zones having divisions for the initial spacing of the opposing game pieces and the safety zones having divisions for the placing of game pieces which have completed the courses.

3. In game apparatus, a game board having courses depicted thereon and divided to represent lines of trenches, each course comprising a plurality of sections and the corresponding sections of the two courses being concentrically arranged, the courses being arranged substantially in the form of two adjacent annuli, two of the sections of one course concentrically encompassing two of the sections of the other course and vice versa, connecting course sections connecting the sections of the courses respectively, and game pieces representing brigades movable over the courses.

4. In game apparatus, a game board having courses depicted thereon and divided to represent lines of trenches, each course comprising a plurality of sections and the corresponding sections of the two courses being concentrically arranged, the courses being arranged substantially in the form of two adjacent annuli, two of the sections of one course concentrically encompassing two of the sections of the other course and vice versa, connecting course sections connecting the sections of the courses respectively, and game pieces representing brigades movable over the courses, the board having also depicted thereon base and safety zones exterior to

the sections of the respective courses, the base zones having divisions for the initial spacing of the opposing game pieces.

5. In game apparatus, a game board having courses depicted thereon and divided to represent lines of trenches, each course comprising a plurality of sections and the corresponding sections of the two courses being concentrically arranged, the course being arranged substantially in the form of two adjacent annuli, two of the sections of one course concentrically encompassing two of the sections of the other course and vice versa, connecting course sections connecting the sections of the courses respectively, and game pieces representing brigades movable over the courses, the board having also depicted thereon base and safety zones exterior to the sections of the respective courses, the base zones having divisions for the initial spacing of the opposing game pieces, the safety zones having likewise divisions for the placing of game pieces which have completed the courses.

6. In game apparatus, a game board having courses depicted thereon and divided to represent lines of trenches, each course comprising a plurality of sections and the corresponding sections of the two courses being concentrically arranged, the board having also depicted thereon base and safety zones exterior to the sections of the respective courses, and game pieces representing brigades movable over the courses, the base zones having divisions for the initial spacing of the opposing game pieces, the board also having depicted thereon a prison zone extending from the base zones.

7. In game apparatus, a game board having courses depicted thereon and divided to represent lines of trenches, each course comprising a plurality of sections and the corresponding sections of the two courses being concentrically arranged, the board having also depicted thereon base and safety zones exterior to the sections of the respective courses, and game pieces representing brigades movable over the courses, the base zones having divisions for the initial spacing of the opposing game pieces, the board also having depicted thereon a prison zone extending from the base zones and likewise a prison zone extending from each of the safety zones, the prison zones at each side of the board meeting end to end.

8. In game apparatus, a game board having courses depicted thereon and divided by cross lines into series of divisions, and game pieces movable over the board and comprising two series for use by opponents playing the game, the game pieces of each series bearing a different combination of ordinals, and no two of the game pieces bearing the same combination considering

the two series collectively as well as individually.

9. In game apparatus, a game board having courses depicted thereon and divided to represent lines of trenches, each course comprising a plurality of sections and the corresponding sections of the two courses being concentrically arranged, the board having also depicted thereon base and safety zones exterior to the sections of the respective course, and game pieces representing brigades movable over the courses, the base

zones having divisions for the initial spacing of the opposing game pieces, the board also having depicted thereon "red" and "white cross" stations at intervals in the length of the cross sections, certain of the game pieces being movable in accordance with the location of the said stations and being suitably designated to indicate their relationship thereto.
